UNITED STATES PATENT OFFICE.

GEORGE H. BOEGER AND JOHN L. CAMPBELL, OF MINNEAPOLIS, MINNESOTA.

DESIGN FOR A MEMORIAL BUTTON.

58,706.

Specification for Design.

Patented Aug. 30, 1921.

Application filed April 2, 1919. Serial No. 287,079. Term of patent 14 years.

To all whom it may concern:

Be it known that we, GEORGE H. BOEGER and JOHN L. CAMPBELL, a citizen of the United States, and subject of the King of Great Britain, respectively, residing at Minneapolis, in the county of Hennepin and State of Minnesota, have invented a new, original, and ornamental Design for a Memorial Button, of which the following is a specification, reference being had to the accompanying drawings, forming part thereof.

The figure is a front elevational view of a memorial button, showing our new design.

We claim:

The ornamental design for a memorial button as shown.

GEORGE H. BOEGER.
JOHN L. CAMPBELL

Witnesses:

S. D. THOMPSON,
THOMAS M. KELLY.
